UNITED STATES PATENT OFFICE

142,684

DESIGN FOR A WATCH BRACELET

William A. Zorichak, Cloquet, Minn.

Application April 26, 1945, Serial No. 119,234

Term of patent 3½ years

(Cl. D45—4)

To all whom it may concern:

Be it known that I, William A. Zorichak, a citizen of the United States, residing at Cloquet, in the county of Carlton and State of Minnesota, have invented a new, original, and ornamental Design for a Watch Bracelet, of which the following is a specification, reference being had to the accompanying drawing, forming part hereof.

Fig. 1 is a top plan view of a watch bracelet, showing my new design with a portion of the center shown broken away, and

Fig. 2 is a side elevational view of Fig. 1.

I claim:

The ornamental design for a watch bracelet, substantially as shown and described.

WILLIAM A. ZORICHAK.
